CLAIM

The ornamental design for a griddle, as shown and described.

DESCRIPTION

FIG. 1 is a perspective view of a griddle showing my new design with a corner pooling area of the griddle at the far corner in the view;

FIG. 2 is perspective view of a griddle showing my new design with a corner pooling area of the griddle at the near corner in the view;

FIG. 3 is a top plan view thereof;

FIG. 4 is a left side view thereof;

FIG. 5 is a bottom plan view thereof;

FIG. 6 is a right side view thereof;

FIG. 7 is a front view thereof; and,

FIG. 8 is a rear view thereof.

The broken lines in the drawings depict environmental subject matter only and form no part of the claimed design.
